UNITED STATES PATENT OFFICE.

JOHN G. LOPATA, OF BERWYN, ILLINOIS.

WINDOW.

1,345,325.

Specification of Letters Patent. Patented June 29, 1920.

Application filed August 30, 1919. Serial No. 320,827.

To all whom it may concern:

Be it known that I, JOHN G. LOPATA, a citizen of the United States, residing at 2333 N. Winfield avenue, Berwyn, Illinois, 5 have invented certain new and useful Improvements in Windows, of which the following is a specification.

The invention relates to windows, and has for its object the provision of a window 10 which may be quickly and conveniently detached from its frame for cleaning, repairing, or other purposes.

A further object of the invention entails the provision of a window which normally 15 is maintained in functional position in a frame, but which may be withdrawn from said frame by a sliding movement whenever access to the window is desired.

It is also an object of the invention to 20 provide a window which comprises a rectangular frame containing a window-pane and an extension hingedly attached to the sash, and which attachment holds the sash to the window-frame so as to maintain the 25 window in operative position.

It is also an object of the invention to provide the window-frame with an auxiliary 30 vertical member to constitute with one of the upright members of the window-frame a narrow opening through which the window may be introduced and removed, as the case may be.

A further object of the invention aims at 35 the provision of a window-sash which has an extension hingedly attached thereto, and which extension has a plate secured thereto constituting an abutment, so that the extent to which the window may be introduced through the narrow space in the window- 40 frame is limited and predetermined.

To the accomplishment of the objects stated and others that will become apparent as the description proceeds, preferred embodiments of the invention are described in 45 the following specification, particularly pointed out in the claims, and illustrated in the accompanying drawings.

In the drawings:

Figure 1 shows in front view a window 50 constructed in accordance with my invention.

Fig. 2 is a side view of the parts shown in Fig. 1.

Fig. 3 is a top plan view of the improved 55 window.

Fig. 4 is a sectional plan view showing a window in operative position in the frame.

Fig. 5 is a front view of a double window constructed in accordance with my invention, with one window shown in operative 60 position while the other is in a partly retracted or withdrawn position.

Fig. 6 is a section on the line 6—6 of Fig. 5.

Referring to the drawings, 1 generally 65 designates the frame of a window or sash comprising the upright members 2, 3 and the horizontal members 4, 5, adapted to receive a window-pane 6. In alignment with the upright member 3, a member 7 is secured 70 thereto by hinges 8, 9. At the outer end of the upright member 7 a plate 10 is secured to the member 7, such that the plate 10 is arranged at right angles to the member 7, and both parts constitute a T. The 75 plate 10 is secured to the member 7 by a plurality of screws 11. As indicated in Fig. 3, the sash 1 may occupy a position constituting an extension of the member 7 or may be oscillated to occupy a position at right 80 angles to the member 7, for a purpose hereinafter further to be described.

The window-frame comprises the vertical members 12, one of which only appears in Fig. 4, and adjacent to one of said vertical 85 members an auxiliary vertical member 13 is provided, which, together with the adjacent vertical member 12, forms a narrow space 14 through which the window proper may be introduced. It is evident that in 90 order to place the window in operative position, the window-frame 1 is introduced from the right to the left through the space 14, as viewed in Fig. 4, until the cross plate 10 abuts with the vertical members 12, 13 95 of the window-frame. Subsequently the sash 1 is swung around the hinges 8, 9 to occupy a position in which the opening 15 is closed. To remove the window-frame for the purpose of cleaning the pane, or for any 100 other purpose, the sash 1 is first placed so as to form an extension of the member 7 and thereupon the operator seizes the T member 10 and withdraws the same together with the member 7 and the window, whereupon convenient access may be had to the window.

In Figs. 5 and 6 the invention is applied to double windows and as shown in this figure, one window is indicated in operative 110

position whereas the other window is partly withdrawn. The construction of the windows is identical to that shown in Figs. 1 to 4. The window-frame shown in Fig. 5 has 5 a window 16, constituting a transom and oscillatable about a horizontal line given by the hinges 17 and 18. As far as this transom is concerned it is of the ordinary construction and does not come within the scope 10 of the present invention. The window-frame comprises the vertical members 19 and 20, the horizontal base member 21, the intermediate horizontal member 22, to which the transom is secured, and auxiliary vertical members 23, 24, arranged adjacent to the vertical members 19 and 20, respectively, for the purpose of defining a space through 15 which the improved windows may be introduced or withdrawn. Through the space 20 25, defined by the vertical members 19 and 23, the window comprising the sash 1, the extension 7, and the cross member 10, may be introduced. The identical window constructed of course symmetrical to the first 25 named window may be introduced through the space 26 defined between the vertical members 20 and 24. In the center of the double window a vertical ledge 27 is provided which at the center is formed with 30 means for securing the windows in closed position.

While the drawings disclose preferred embodiments of the invention, they are merely indicative of the principle on which the invention is predicated. It is therefore not my intention to confine myself to the details exactly as shown, but I desire to claim the invention as broadly as the state of the art permits.

40 I claim:

1. In combination with a window-frame, comprising vertical and horizontal members, an auxiliary member defining with one of said first named members a narrow opening, 45 a sash containing a pane adapted to be introduced through said narrow opening, and means for securing said sash in said frame and permitting said sash to be arranged in functional position.
- 50 2. In combination with a window-frame, comprising vertical and horizontal members, an auxiliary member defining with one of said first named members a narrow opening, a sash containing a pane adapted to be introduced through said narrow opening, an 55

extension hingedly connected to said sash and adapted to permit introduction of said sash into said opening sufficient to be swung into operative position.

3. In combination with a window-frame, 60 comprising vertical and horizontal members, an auxiliary member defining with one of said first named members a narrow opening, a sash containing a pane adapted to be introduced through said narrow opening, an 65 extension hingedly connected to said sash, and an abutment at the free end of said extension and of a width in excess of the width of said narrow opening.

4. In combination with a window-frame, 70 comprising vertical and horizontal members, an auxiliary member defining with one of said first named members a narrow opening, a sash containing a pane adapted to be introduced through said narrow opening, a bar, 75 hingedly connected to said sash, and an abutment at the free end of said bar and being wider than said opening, said bar being of a width sufficient to permit said sash to be swung into closing position.

5. In combination with a window-frame, comprising vertical and horizontal members, an auxiliary member defining with one of said vertical members a narrow opening, 85 a sash containing a pane adapted to be introduced through said narrow opening, a bar hingedly connected to said sash, and an abutment at the free end of said bar and being wider than said opening, said bar being of a width sufficient to permit said sash to be swung at right angles thereto.

6. In combination with a window-frame, comprising vertical and horizontal members, auxiliary members defining with said vertical members narrow openings, a plurality of sashes each containing a pane adapted to be introduced through one of said narrow openings, a bar hingedly connected to each of said sashes, and an abutment at the free end of said bar and being wider than said opening, said bar being of a width sufficient to permit said sashes to be swung at right angles thereto, and said sashes being constructed to constitute a closure for the opening between said auxiliary window-frame members, substantially as described.

In witness whereof I affix my signature.

JOHN G. LOPATA.
